UNITED STATES PATENT OFFICE.

WENZEL SCHEICK, OF WATERBURY, CONNECTICUT.

AIR-INJECTOR.

1,155,620.

Specification of Letters Patent.

Patented Oct. 5, 1915.

Application filed February 3, 1915. Serial No. 5,857.

To all whom it may concern:

Be it known that I, WENZEL SCHEICK, a citizen of the United States, and resident of Waterbury, in the county of New Haven and State of Connecticut, have invented certain new and useful Improvements in Air-Injectors, of which the following is a specification.

My invention relates to an improved form 10 of air injecting apparatus and is designed especially for introducing a blast of cold air into beer vats, while cleaning and refinishing the same.

Vats or tanks employed in the production 15 of beer have to be scraped and revarnished upon the inside once or twice a year in order to keep them clean and wholesome. Thus it is necessary after drawing off the liquid beverage to send one or two men into the 20 tank, first to dry it out, then to scrape the inner walls and finally to shellac and varnish the same. The alcohol fumes from the shellac are very strong and frequently the men are overcome thereby unless suitable 25 precautions are taken to prevent it.

I have therefore devised my present invention for the purpose of injecting fresh air into tanks of this sort while the men are at work therein and so that the inflowing 30 air may be directed against and into the faces, if necessary, of the workmen, while engaged in the varnishing operation.

The object therefore of the invention is to provide a simple and practical form of portable injector which can be readily placed in front of a beer tank and put in operation and as easily shifted from one tank to another; to construct the injector so that but a small quantity of compressed air will be 40 required, and may be used with a larger quantity of atmospheric air; further to employ a portable stand for supporting the device having adjustable connections whereby the tube can be raised and lowered or adjusted to line with the manhole in the tank and in a manner to provide for throwing the blast of air into any portion of the tank required.

With these and other objects in view the 50 invention resides and consists in the construction and novel combination and arrangement of parts hereinafter more fully described, illustrated in the accompanying drawings, and pointed out in the claim 55 hereto appended, it being understood that various changes in the form, proportion,

size and minor details of construction within the scope of the claim may be resorted to without departure from the spirit or sacrificing any of the advantages of the invention.

Similar characters of reference denote like or corresponding parts throughout the several figures of the accompanying drawings forming a part of this specification and upon which—

Figure 1 shows an elevation of a beer tank with my improved injector arranged in front thereof and in position for operation. Fig. 2 is a larger side view of the injector 70 with the tube in a different position and Fig. 3 is a transverse cross section of the injector and stand taken on line 3—3 of Fig. 2.

Referring in detail to the characters of 75 reference marked upon the drawings 5 represents the beer tank, 6 a vent pipe in the top of the tank, 7 an inlet and outlet pipe by means of which the liquid is run into and out of the vat. 8 is a cock in the supply pipe 80 7 by means of which the passage of the fluid therethrough is controlled.

9 represents a man hole in the front of the tank and through which the workmen enter 85 the tank to clean and refinish the same.

The invention proper is more clearly shown in Fig. 2 and as will be noted comprises a portable stand including a heavy base 10 in which is secured a vertical upright 11. Upon this upright is mounted an 90 adjustable bracket 12 that may be raised and lowered upon the upright and secured at various elevations by means of a set screw 13. This bracket is provided with an extension 14 that is provided with a socket in 95 which the shank 15 of a forked support 16 is seated. This support may be adjusted to various positions in the bracket and is secured by means of a set screw 17. The end portions of the two divisions of the support 100 16 are provided with holes 18 in which a supporting pipe 19 is secured. This pipe serves the double purpose of supporting the tube 20 and as a means of introducing air into the tube. The tube so called comprises 105 a length of relatively large pipe the ends of which are open and which has an unobstructed air passage therethrough. The pipe extends crosswise through the center of the tube and is provided with a series of small 110 outlet holes 21 to admit the air into the tube that is arranged to swing upon it so that the

tube may be readily changed from one position to another upon the pivot.

I connect a valve 22 to one end of the perforated pipe 19 and to this valve is attached a flexible pipe 23 that in turn is connected with a compressed air supply, not shown. It will thus be seen that when the valve is open and the compressed air supply turned in, the said inflow of compressed air will serve to draw in the cold air from the atmosphere and carry it through the pipe and force it out from the discharge end 23.

This form of device insures a relatively larger volume of fresh air being supplied in the vat with the use of a comparatively small quantity of compressed air and further provides for the distribution of the air in any section of the tank by the assistance of an attendant on the outside in charge of the device and who merely adjusts the nozzle to the various positions required to send the air in such sections of the tank as may be desired.

Copies of this patent may be obtained for five cents each, by addressing the "Commissioner of Patents, Washington, D. C."

Having thus described my invention what I claim and desire to secure by Letters Patent is:—

An air injecting apparatus of the class described, the same comprising a stand including a base and upright, a bracket adjustably mounted thereon, a support adjustably mounted in the bracket and provided with outwardly disposed forks having holes in their end portions, a perforated pipe supported in the holes of the forks, a tube pivotally mounted on the pipe and covering the perforations, a valve connected to the pipe and a compressed air supply pipe connected with the valve to supply air to the perforated pipe and tube.

Signed at Waterbury in the county of New Haven and State of Connecticut this 29 day of January A. D., 1915.

WENZEL SCHEICK.
